Attorneys.

UNITED STATES PATENT OFFICE.

AXEL FILIP WALDEMAR STÄHLBERGER, OF DUMBARTON, SCOTLAND.

STOCKLESS ANCHOR.

1,112,864.

Specification of Letters Patent.

Patented Oct. 6, 1914.

Application filed April 6, 1914. Serial No. 829,771.

To all whom it may concern:

Be it known that I, AXEL FILIP WALDEMAR STÄHLBERGER, a subject of the King of Sweden, residing at Dumbuck Hotel, 5 Dumbarton, Scotland, have invented certain new and useful Improvements in Stockless Anchors, of which the following is a specification.

This invention relates to anchors of the 10 stockless type each having a bifurcated shank and a plurality of flukes, and it has for its object to improve their construction in such manner that enhanced strength and greater gripping efficiency and holding 15 power and, consequently, less weight in a ship's anchor equipment, is attained while the shank shall be of proportionately less length, thereby rendering the anchor more easy of housing.

20 In order that the invention may be clearly understood I have hereunto appended an explanatory sheet of drawings whereon I have shown, in Figures 1 and 2, front and side sectional elevations, respectively, of a 25 preferred form of anchor constructed in accordance with my invention.

As illustrated, the anchor comprises a bifurcated shank N the arms F of which have enlarged bosses E at the lower ends thereof 30 in which is mounted a rod or spindle D. Freely and independently mounted upon bushings on the rod or spindle D are three main gripping flukes A, B and C of substantially equal length and the central one, 35 B, of which is normal to said rod while the outer ones, A and C, are splayed. The rod D and, with it, the flukes A, B and C are held in assembled position by nuts G upon the screwed ends of the rod, or by 40 other convenient means, said nuts being locked by rivets or other suitable means.

The flukes A, B and C may be provided with webs H extended to act as tripping blades additional to the usual tripping 45 blades I which are so shaped as to be adapted to act as gripping blades also and the sides of which are undercut to co-act with tapered faces J on the bosses E for limiting their angular travel. The tripping blades 50 or projections on the fluke members co-act with the shank to form overstops.

The head K of the shank is rounded to receive the usual shackle L while two inwardly projecting parts M are provided thereon which, while they retain the shackle 55 when it is in place, permit of its passage so

that it may be entered into position. Alternatively, a cross bolt or cross band may be used to keep the shackle in position.

It sometimes occurs that, owing to irregularity of the surface or inequality of the nature of the bottom, it is impossible for all the flukes of an anchor to grip simultaneously. Under these conditions, with an anchor having two or more flukes capable only of simultaneous movement, it is possible that one, or more than one, fluke may grip while the other, or others, is, or are, brought into contact with a portion of the bottom which it, or they, cannot enter, thereby preventing the fluke, or flukes, which has, or have, already taken a grip entering to its, or their, full extent. With an anchor constructed in accordance with the present invention, however, owing to the flukes being independently pivoted, one, or more than one, fluke may grip and enter the bottom to its full extent without being affected by the remainder while, owing to the tripping blades being adapted to act as gripping blades also, the tripping blades of those flukes which do not grip may enter the bottom and will prevent said latter flukes affecting those which have already entered. Further, the bifurcated arms F and the rod E constitute a complete triangle so that, no matter which of the flukes grip, 80 no bending moment will be applied to the shank.

Although I have, by way of illustration or example, illustrated and described a preferred form of my invention it will be understood that numerous structural modifications may be made without departing from the spirit of the invention as defined by the 90 succeeding claims.

Having now fully described my invention, what I claim and desire to secure by Letters Patent is:—

1. An anchor comprising a bifurcated shank and independently pivoted flukes within and without said shank.

2. An anchor comprising a bifurcated shank, a pivoted fluke within said shank and independently pivoted flukes without said shank.

3. An anchor comprising a bifurcated shank, a rod carried by said shank, a plurality of flukes turnably and independently mounted on said rod, one being within and the remainder without said shank.

4. An anchor comprising a bifurcated

- shank, a pivoted fluke within said shank and normal to its pivot and independently pivoted splayed flukes without said shank.
5. An anchor comprising a bifurcated shank, independently pivoted flukes within and without said shank and tripping blades on said flukes.
6. An anchor comprising a bifurcated shank, independently pivoted flukes within and without said shank and tripping blades adapted to act also as gripping blades on said flukes.
7. An anchor comprising a bifurcated shank, a rod carried by said shank, a plurality of flukes turnably and independently mounted on said rod, tripping blades adapted to act also as gripping blades on said flukes and extensions on said shank adapted to co-act with said tripping blades to limit the movement of said flukes.
8. An anchor comprising a bifurcated shank, a rod carried by said shank and forming a complete triangle therewith, a plurality of flukes turnably and independently mounted on said rod, one being within and the remainder without said shank and tripping blades on said flukes adapted to co-act with said shank to limit the movement of said flukes.
9. An anchor comprising a bifurcated shank, independently pivoted flukes within and without said shank, tripping blades on said flukes and webs, adapted to act as additional tripping blades, on said flukes. 30
10. An anchor comprising a bifurcated shank, independently pivoted flukes within and without said shank, tripping blades adapted to act also as gripping blades on said flukes and webs, adapted to act as additional tripping blades, on said flukes. 35
11. An anchor comprising a bifurcated shank, inwardly projecting parts on the arms of said shank, a shackle which is adapted to pass said projecting parts and independently pivoted flukes within and without 40 said shank.
12. An anchor comprising a bifurcated shank, a fluke within said shank and flukes without said shank, said first mentioned fluke being capable of movement independently of the other flukes. 50

In testimony whereof I affix my signature in presence of two witnesses.

AXEL FILIP WALDEMAR STÄHLBERGER.
